UNITED STATES PATENT OFFICE.

WORLEY LEAS, OF KOKOMO, INDIANA.

IMPROVED BELT-CO尤LING.

Specification forming part of Letters Patent No. 56,767, dated July 31, 1866.

To all whom it may concern:

Be it known that I, WORLEY LEAS, of Kokomo, in the county of Howard and State of Indiana, have invented a new and useful Improvement in Belt-Couplings; and I do hereby declare the following to be a full, clear, and exact description of the nature, construction, and operation of the same, reference being had to the accompanying drawings, which are made a part of this specification, and in which—

Figures 1 and 3 are plans of a belt with my invention applied. Figs. 2 and 4 are longitudinal sections of the same on the line $x x$, Figs. 1 and 2.

Similar letters of reference indicate corresponding parts in the several figures.

My invention consists in connecting the ends of a belt by means of two bent metallic plates and a link, the bent plates having sockets to receive the two long sides of the link, and thereby form a joint-connection which permits the necessary deflection of the belt in circulating around a drum or pulley, and at the same time affords a cheap and strong connection.

So far as this connection is concerned, the plain oblong link may be sufficient in carrying out the above feature of my invention; but the invention further consists in providing the link with a longitudinal central rib or back, which gives a continuous unbroken character to the belt, and constitutes a point of attachment for strips or pieces of leather or analogous material, which are applied, as hereinafter described, so as to prevent slipping when the coupled portion of the belt is on the pulley or drum.

The following description will enable others skilled in the art to which my invention appertains to fully understand and use the same.

The drawings represent four sections or parts of a belt, A B C C', which are connected by the links D D and the metallic plates E E E E, all of which are formed and applied alike, the same being sprung upon the ends of the belt and securely fastened thereto by rivets. One of the links D, as will be seen from

Figs. 1 and 2 of the drawings, is simply a plain open link, the two sides of which constitute the pintles which work loosely within the contiguous ends of the bent plates E E, which thus form the leaves of a double hinge. At this point of connection between the two belts slipping is prevented by means of the strip of leather or analogous material, F, which is secured upon and over that side of the hinge which moves upon the pulley or drum.

The link at the other point of connection represented in the drawings, Figs. 3 and 4, is of peculiar form, the same having a rib or back, D', extending longitudinally of the link and jointed thereto at both ends. This rib assists in the attachment of the leather strip F', which is passed under the rib, brought up on the two opposite sides of the belt, and fastened by rivets. The side of the rib D' which comes against the pulley is covered by a strip of leather, G, which is held on by screws g, which pass one within the other from the two opposite sides of the ribs and strip, as represented. The rib or back D' affords a continuous bearing and a convenient attachment for the strip G.

Having thus described my invention, the following is what I claim as new and desire to secure by Letters Patent:

1. A belt-coupling consisting of a link, D, and bent metallic plates E E, connected together so as to form a joint at each side of the link, substantially in the manner specified.

2. The rib or back D', formed on the link D, and employed to form a continuous bearing for the leather, as described.

3. In combination with a belt-coupling constructed as herein described, the leather covering F, F', and G, to prevent slipping when the coupling is upon the pulley.

To the above specification of my improvement in belt-couplings I have signed my hand this 23d day of March, 1866.

WORLEY LEAS.
